(57) CLAIM

The ornamental design for a bottle, as shown and described.

DESCRIPTION

FIG. 1 is a top, front and right side perspective view of the bottle;

FIG. 2 is a rear elevational view thereof;

FIG. 3 is a front elevational view thereof; and

FIG. 4 is a view of the left side of the bottle, the right side view being a mirror image of the side view shown.

FIG. 5 is a top plain view of the bottle; and,

FIG. 6 is a bottom plain view thereof.

The broken line showing is for illustrative purpose only and forms no part of the claimed design.

1 Claim, 5 Drawing Sheets
